UNITED STATES PATENT OFFICE.

NEWMAN H. HOLLAND, OF WEST ORANGE, NEW JERSEY, ASSIGNOR TO THOMAS A. EDISON, INCORPORATED, OF WEST ORANGE, NEW JERSEY, A CORPORATION OF NEW JERSEY.

ANTIVIBRATION DEVICE FOR CENTRIFUGAL GOVERNORS.

1,071,744.

Specification of Letters Patent.

Patented Sept. 2, 1913.

Application filed August 17, 1912. Serial No. 715,546.

To all whom it may concern:

Be it known that I, NEWMAN H. HOLLAND, a subject of the King of Great Britain, and a resident of West Orange, in the county 5 of Essex and State of New Jersey, have invented certain new and useful Improvements in Antivibration Devices for Centrifugal Governors, of which the following is a description.

10 My invention relates to anti-vibration devices for centrifugal governors and more particularly to such a device as applied to governors of the type in which a plurality of weighted spring arms are movable outwardly under the action of centrifugal force.

In all machines, especially in those provided with motors, vibrations are created by the operation of the machine. For example, 20 in an Edison business phonograph, such vibrations originate mainly in the motor and are probably augmented by other parts of the phonograph, in the operation thereof. When a centrifugal governor, especially one 25 having a plurality of weights mounted on spring arms, is used on such a machine for controlling its speed, or for other purposes, the governor is very liable to partake of and amplify these vibrations. To obtain the 30 best working conditions, it is, of course, desirable in all machines, to eliminate vibrations thereof in so far as it is possible to do so, and especially is this the case in an apparatus such as a phonograph where the result 35 thereof is imperfect recording or reproducing.

The objects of my invention are to prevent a governor from partaking of and amplifying the vibrations of a machine to 40 which it is applied and to provide simple and efficient means for accomplishing this result.

In order that my invention may be more clearly understood, attention is directed to 45 the accompanying drawings forming a part of this specification, in which the same reference characters are used to designate corresponding parts throughout, and in which:

Figure 1 is an elevation of a motor for a 50 phonograph provided with a centrifugal speed governor having an anti-vibration device applied thereto, in accordance with my invention. Fig. 2 is an end elevation of the

governor with the anti-vibration device applied thereto, as shown in Fig. 1; and Fig. 55 3 is an enlarged cross sectional view on line 3—3 of Fig. 1.

Referring to the drawings, reference character 1 represents a motor, which is here shown as an electric motor of the type usually employed in Edison business phonographs. The motor is suitably attached to the supporting plate 2 and power may be taken from the shaft 3 thereof by means of pulley 4 and belt 5. In order to control the speed of the motor 1, I provide brake mechanism comprising any suitable centrifugal governor 6 adapted to coöperate with an adjustable brake arm 7 provided with friction pads 8. In the device shown in the drawing, the governor 6 comprises a shaft, forming an extension of the motor shaft 3, a collar 9 fixed to the shaft, a collar 10 loose on the shaft and carrying the usual friction disk 11 adapted to coöperate with the friction pads 8 of the brake arm 7, and a plurality of bowed spring arms 12 connected to the collars 9 and 10 and weighted between their ends by means of weights 13. It will be obvious that the governor will tend to partake 80 of and amplify any vibrations of the motor 1, and this tendency is very pronounced in the specific form of governor herein illustrated, due to the employment of the weighted spring arms 12. In order to prevent this tendency of the governor as much as possible, I provide suitable means, such as an endless helical steel spring 14, for embracing the bowed spring arms 12, and which will remain in contact therewith no 90 matter what the relative positions of the spring arms. It will be apparent that any outward movement of any arm or arms 12 will be resisted by the spring 14, as such movement would expand the spring. Suitable means is provided for maintaining the helical spring 14 in proper position on the spring arms 12. This means, as shown, comprises a pair of arms 15, each of which is formed with offset ends 16 and 17, one end 100 16 being suitably secured to collar 9, as by a screw 18, which may also serve to attach one of the spring arms 12 to the collar, and the other end 17 of which contacts the spring 14.

Having now described my invention, what

I claim as new therein and desire to protect by Letters Patent is as follows:—

1. The combination with a centrifugal governor having a plurality of outwardly movable weighted arms, of means unattached to but embracing and contacting said arms for preventing vibrations of the governor, substantially as described.
2. The combination with a centrifugal governor having a plurality of outwardly movable weighted arms, of a spring unattached to but embracing and contacting said arms for preventing vibrations of the governor, substantially as described.
3. The combination with a centrifugal governor having a plurality of outwardly movable weighted arms, of an endless helical spring unattached to but surrounding and contacting said arms for preventing vibrations of the governor, substantially as described.
4. The combination with a centrifugal governor having a plurality of outwardly movable weighted arms, of an endless helical spring unattached to but surrounding and contacting said arms, and means for maintaining the spring in position on said arms, substantially as described.
5. The combination with a centrifugal governor having a plurality of outwardly movable weighted arms, of an endless helical spring unattached to but surrounding and contacting said arms for preventing vibrations of the governor, substantially as described.
6. The combination with a centrifugal governor comprising a shaft, a loose collar and a fixed collar mounted thereon, a plu-

rality of spring arms connecting the collars, and weights carried by the spring arms intermediate their ends, of an endless helical spring surrounding and contacting the spring arms between the weights and the fixed collar, and means attached to the fixed collar for retaining the endless spring in position on the arms, substantially as described.

7. The combination with a centrifugal governor comprising a shaft, a loose collar and a fixed collar thereon, a plurality of bowed spring arms connected at their opposite ends to the collars, and weights carried by the spring arms intermediate their ends, of an endless helical spring surrounding and contacting the spring arms between the weights and the fixed collar, and a plurality of members secured to the fixed collar and engaging the endless spring to properly position the same, substantially as described.

8. The combination with a centrifugal governor comprising a shaft, a loose collar and a fixed collar mounted thereon, and a plurality of outwardly movable weighted arms connecting said collars, of an endless spring surrounding and contacting the weighted arms, and means attached to one of said collars for retaining the endless spring in position on said arms, substantially as described.

This specification signed and witnessed this 16th day of August 1912.

NEWMAN H. HOLLAND.
